UNITED STATES PATENT OFFICE.

FREDERICK S. DELLENBAUGH, OF NEW YORK, N. Y.

HOLLOW AUGER.

SPECIFICATION forming part of Letters Patent No. 254,286, dated February 28, 1882.

Application filed April 21, 1881. (No model.)

To all whom it may concern:

Be it known that I, FREDERICK S. DELLENBAUGH, of New York, in the county of New York, and in the State of New York, have invented certain new and useful Improvements in Hollow Bits; and I do hereby declare that the following is a full, clear, and exact description thereof, reference being had to the accompanying drawings, and to the letters of reference marked thereon, making a part of this specification.

This invention relates to an improved boring-tool or auger; and it has for its objects to provide a tool or bit which may be employed in connection with a brace or other device, and whereby a circular aperture may be produced in the material to be bored with greater facility and expedition than heretofore, while the tendency to split the material will be materially lessened, if not wholly obviated, and a truer and smoother aperture produced. These objects I attain by the devices illustrated in the accompanying drawings, in which—

Figure 1 represents a view showing my improved bit attached to a brace. Fig. 2 represents a detached perspective view of my improved bit, and Fig. 3 represents a sectional view of the same.

The letter A indicates the bit, which consists of a cylinder, of steel, having a boss or head, B, at the upper end, adapted to fit in the socket in the drill-brace, and apertures by which it may be held by the screw or spring-catch thereof. The other end of said cylinder is provided with a series of saw-teeth, C, inclined in the same direction, as clearly indicated in the drawings. The said teeth may be

set, if desired, in the same manner as an ordinary saw, and the inclination or angle may be varied according to the material to be bored, 40 whether hard or soft.

It will be seen from the above description that I have an auger-bit which has an opening of the same diameter entirely through it, so that when it is used in combination with the 45 angular brace the core will pass through the socket of the brace. It is not intended by my invention to make saw-dust or shavings of the core, but to bore through a plank or beam and allow the solid core to pass freely. It is also 50 essential to my invention to have the upper end of the hollow bit re-enforced, so that the bit can be secured rigidly to the socket of the breast-brace, without bending or crushing the bit, and without the necessity of using such a 55 fastening as would interfere with the expulsion of the core.

Having thus described my invention, what I claim and desire to secure by Letters Patent, 60 is—

The combination of the tubular bit, the serrations C, the shoulder a, the brace H, having the angular curves, the socket G of the brace, having an opening through it, and means for securing the bit to the brace, substantially as 65 described.

In testimony whereof I affix my signature, in presence of two witnesses, this 14th day of April, 1881.

FREDERICK S. DELLENBAUGH.
